UNITED STATES PATENT OFFICE.

JOHN M. FALLER, OF JACKSONVILLE, FLORIDA.

RAILWAY-SWITCH.

No. 902,866.

Specification of Letters Patent.

Patented Nov. 3, 1908.

Application filed March 2, 1908. Serial No. 418,841.

To all whom it may concern:

Be it known that I, JOHN M. FALLER, a citizen of the United States, residing at Jacksonville, in the county of Duval and State of Florida, have invented certain new and useful Improvements in Railway-Switches, of which the following is a specification, reference being had to the accompanying drawings:

10 My invention relates to improvements in railway switches and operating devices therefor.

One object of the invention is to provide a safety switch which must be manually opened to permit a train to pass from the main track to the siding or branch, and which will be automatically closed after the train has cleared it so that a second train will continue past the switch upon the main 20 track, thus avoiding the danger of wrecks caused by one train running into another on a siding where the switch is left open through carelessness.

Another object of the invention is to provide a switch of this character with an improved means whereby it may be manually opened and whereby it will be held open by track devices actuated by the cars of the train.

30 A further object of the invention is to provide an improved track device which is operated by passing cars and which may be employed for operating a switch, signal or the like.

35 With the above and other objects in view, the invention consists of the novel features of construction and the combination and arrangement of devices hereinafter fully described and claimed, and illustrated in the 40 accompanying drawings, in which

Figure 1 is a plan view of a portion of a main track and a siding, showing the application of my improved switch and track device thereto; Fig. 2 is an enlarged detail 45 plan view of portions of the switch points and the manual operating devices therefor; Fig. 3 is a vertical section taken on the plane indicated by the line 3—3 in Fig. 2; Fig. 4 is an enlarged side elevation of a portion of 50 the track device for holding the switch open; Figs. 5, 6 and 7 are vertical sectional views taken respectively on the planes indicated by the lines 5—5, 6—6, and 7—7 in Fig. 4; and Fig. 8 is a detail vertical longitudinal

section through the inner ends of the raised 55 or movable track rails.

In the drawings 1 and 2 denote the rails of the main track, 3 and 4 the rails of the side track or branch, and 5 and 6 the movable switch points. These points are connected, adjacent to their free ends, by a tie rod 7 and by an operating rod or bar 8 which extends beneath one of the track rails and between two of the cross ties 9. The inner portion of the bar 8 carries attaching 65 brackets 8^a secured to the switch points 5, 6, as clearly shown in Fig. 3, and its outer end is bifurcated to receive one end of a 70 slideably operating rod 10, a pivot bolt 11 uniting said ends of the parts 8, 10. The rod 10 extends at right angles to the track and is 75 slidably mounted in a rectangular frame 12 secured by bolts 13 upon the extended portions of two of the ties 9. The rod 10 is spring actuated in a direction to cause it to 80 close the switch, by a coil spring 14 which surrounds it and is confined between one of the cross pieces of the frame 12 and an adjustable stop collar or sleeve 15 which is 85 locked in an adjusted position by a nut 16 engaged with the threaded portion of said rod. The outer end of the rod 10 slides in an intermediate cross piece of the frame 12 and has secured upon it a bifurcated block or head 17 in which is pivoted one end of a 90 link 18. This link has pivoted in its other bifurcated end an upright hand lever 19 which is fulcrumed upon the bolt 20 arranged in bearing brackets 21 upon the outer end of the frame 12.

From the foregoing it will be seen that the spring 14 exerts its energy to close the switch and that when it is desired to open the same it is necessary to operate the hand lever 19 in a direction that will slide the rod 95 10 inwardly or toward the switch points.

22 denotes a bell crank pivoted at its angle on a vertical pivot 23 arranged in a bracket 24 upon the frame 12. One arm 25 of the bell crank is bifurcated to receive the 100 collar 15 and in its spaced portions are formed longitudinal slots 26 to receive pivot studs 27 projecting in opposite directions from the collar 15. The other arm 28 of the bell crank 22 carries a transverse pivot 29, 105 the ends of which project into longitudinal slots 30 formed in a bifurcated block 31 secured upon one end of a rod 32.

- For the purpose of retaining the switch in its open position after it has been manually opened and during the time a train is passing through it, I provide the track device shown more clearly in Figs. 4 to 8, inclusive of the drawings, which device operates and controls the rod 32. Said track device comprises two raised track rails 33, 34 which are arranged end to end and included in the track of the siding. The rails 33, 34 have their outer ends suitably hinged to the track rails 4 so that they can swing vertically and their opposing inner ends are connected together for simultaneous movement by gear segments 35, 36 formed on the ends of blocks 37, 38 in the form of castings which fit the meeting ends of the rails 33, 34 and are secured thereto by transverse bolts 39. The blocks or castings 37, 38 have their lower ends extended beneath the inner ends of the rails 33, 34 and in the opposite side faces of the lower portion of the block 38 are recesses which form horizontal flanges 41. To the latter is secured a U-shaped bolt 25 or clip 42 which depends from the block 38 and loosely receives the curved free end of an arm 43 secured to a horizontal shaft or pivot 44 mounted for rotation in suitable bearings 45 upon longitudinal sleepers or beams 46 arranged beneath the cross ties. Fixed to the shaft or pivot 44, outside of the vertical plane of the raised or movable track rails is an arm 47 which is pivoted in the bifurcated end of the rod 32 or a rod which is suitably connected to said rod 32.
- The outer ends of the raised track rails 33, 34 are pivoted or hinged to the track rails 4 by securing to the meeting ends of said rails, by bolts or the like 48, cast blocks 49, 50, as more clearly shown in Figs. 4 and 5. The hinge blocks 50 upon the rails 33, 34 are formed at their ends with spaced projecting ears 51 to engage the outer side faces of the hinge blocks 49 to which latter they are connected by transverse pivot bolts 52.
- The track rails 33, 34 are adapted to be depressed by a car or cars passing over them and they are held elevated or off of the cross ties arranged beneath them on the sleepers 46, by spring devices arranged at suitable intervals between their ends. One of these spring devices is clearly shown in Figs. 4 and 6 and consists of a plate 53 secured by bolts 54 to the bottom of one of said raised rails and having, depending from the center of its under face, a guide stud 55 which slides in a vertical bore or opening 56 formed in a cast frame or block 57 which is arranged upon one of the sleepers 46 and between two of the cross ties 9 and has flanges or portions 58 which are bolted to said ties and sleeper. A coil spring 59 surrounds the stud or projection 55 and has its upper end bearing against the bottom of the plate 53 and its lower end arranged in an enlarged upper portion of the bore 56 and bearing upon a shoulder 60 formed in said bore by enlarging its upper end. It will be seen that these spring devices will hold the vertically movable rails 33, 34 in their elevated position shown in Fig. 4 and that when a train passes over them they will be moved downwardly into contact with the cross ties 9.
- In order to prevent the raised or movable rails 33, 34 from spreading or moving away from the track rail 3, I provide, at suitable intervals between said rails, tie rods or links 61 which have bifurcated ends pivotally connected to eye bolts 62, 63 arranged, respectively, in the track rails 3 and the raised rails 33, 34, as clearly shown in Figs. 5, 6 and 7. While in Fig. 1 of the drawings I have shown the track device arranged in the siding some distance from the main line, it will be understood that it may be located as close to the switch as may be found practical.
- The operation of the invention is as follows. The spring 14 will hold the switch normally in its closed position so that trains may pass in either direction upon the main track without operating said switch. When it is desired to enter the siding, the lever 19 must be manually operated to move the switch points 5, 6 to their open position and the lever must be held until the train enters the siding and its locomotive passes upon the raised track rails 33, 34. As long as said rails 33, 34 are depressed by the locomotive or one of the cars of the train, the switch will be held open since the depression of said rails will cause the bell crank formed by the levers 43, 47 to actuate the rod 32 so that the slotted head 31 on the latter will hold the bell crank 22 in the position which it assumes when the hand lever 19 is operated to open the switch. The instant the raised rails 33, 34 are released, their spring devices will elevate them and the rod 32 will be moved in the opposite direction so as to release the bell crank 22, whereupon the spring 14 closes the switch. It will thus be seen that the invention will dispense with the necessity of the switch being held open manually until the entire train passes through the same and will obviate the danger of the switch being left open through carelessness or forgetfulness. Consequently it will be impossible for wrecks to occur owing to the trains passing through open switches and into sidings already occupied by other trains.
- While I have shown and described in detail the preferred embodiment of my invention, it will be understood that I do not wish to be limited to the precise construction set forth and that various changes in the form, proportion, and minor details may be resorted to without departing from the spirit

or sacrificing any of the advantages of the invention.

Having thus described my invention what I claim is:

5. 1. The combination of a switch, spring actuated to its closed position, means for actuating said switch to its open position, and a track device including raised track rails for holding the actuating means against 10 movement while a train is passing through the switch.
2. The combination with a main line and a siding, of a switch, a slideable operating rod for the switch, a spring for actuating said rod in one direction to close the switch, a lever for actuating said rod in the opposite direction to open the switch, a bell crank having one arm operatively connected to said rod, a track device including raised 15 track rails, an operating rod actuated by said raised track rails and a loose connection between said operating rod and the other arm of the bell crank.
3. The combination with a main line and 20 a siding, of a switch, a slideable operating rod for the switch, a spring for actuating said rod in one direction to close the switch, a lever for actuating said rod in the opposite direction to open the switch, a bell crank having one arm operatively connected to 25 said rod, a track device including raised track rails, a second bell crank having one arm actuated by said track rails, and an operating rod connected to the other arm of the first mentioned bell crank.
4. The combination with a main line and 30 a siding, of a switch, a slideable operating rod for the switch, a spring for actuating said rod in one direction to close the switch, a lever for actuating said rod in the opposite direction to open the switch, a bell crank having one arm operatively connected to 35 the last mentioned bell crank and having a loose connection with the second arm of the first mentioned bell crank.
5. The combination with a main line and 40 a siding, of a switch, a slideable operating rod for the switch, a spring for actuating said rod in one direction to close the switch, a lever for actuating said rod in the opposite direction to open the switch, a bell crank having one arm operatively connected to 45 said rod, a track device including raised track rails arranged in the siding, said raised track rails having their outer ends hingedly connected to the stationary track rails and their inner ends provided with meshing gear seg- 50 ments, spring devices for elevating said raised track rails, a yoke depending from the inner end of one of the raised track rails, a horizontal shaft, an arm upon the latter loosely engaged with said yoke, a sec- 55 ond arm upon said shaft, a rod pivoted to the last mentioned arm, and a loose connection between said rod and the second arm of said bell crank.
6. The combination with stationary track 60 rails, of vertically movable track rails having their outer ends hingedly connected to the stationary ones and their inner ends provided with meshing gear segments, spring devices for elevating said movable track rails, and an actuating device operated by 65 said movable track rails.
7. The combination with stationary track rails, of vertically movable track rails having their outer ends hingedly connected to the stationary ones and their inner ends provided with meshing gear segments, spring devices for elevating said movable track rails, a bell crank having one arm operatively connected to one of the movable track rails, and an operating rod connected 70 to the other arm of the bell crank.
8. The combination with stationary track rails, of vertically movable track rails having their outer ends hingedly connected to the stationary ones and their inner ends provided with meshing gear segments, spring devices for elevating the movable track rails, a yoke depending from the inner end of one of the movable track rails, a horizontal shaft, an arm upon said shaft and 75 loosely engaged with said yoke, a second arm upon said shaft, and an operating rod connected to the second mentioned arm.
9. The combination of a track having vertically movable track rails arranged in one 80 of its sides, and tie rods or links between the movable rails and the rails of the other side.
10. The combination of a track having a vertically movable track rail, a casing arranged beneath the movable track rail and having a vertical opening, a guide stud depending from the movable track rail and 85 slideable in an opening in the casing and a spring surrounding said stud for elevating the movable track rail.
11. The combination of a track having a vertically movable rail, a plate secured to the base of the movable rail and having a depending stud, a casing arranged beneath 90 the movable rail and having a vertical bore or opening to receive said stud, said bore or opening being formed with a shoulder, and a coil spring surrounding the stud and confined between said shoulder and said plate. 95

In testimony whereof I hereunto affix my signature in the presence of two witnesses.

JOHN M. FALLER.
